UNITED STATES PATENT OFFICE.

LEAL L. MONTGOMERY, OF SUPERIOR, WISCONSIN.

MIXER.

Application filed June 24, 1920. Serial No. 391,343.

To all whom it may concern:

Be it known that I, LEAL L. MONTGOMERY, a citizen of the United States, and a resident of Superior, in the county of Douglas and 5 State of Wisconsin, have invented a new and Improved Mixer, of which the following is a full, clear, and exact description.

This invention relates to improvements in mixers, and more particularly to a mixer 10 for use in connection with internal combustion engines, an object of the invention being to provide a mixer which can be manufactured and sold at an extremely low price and which can be conveniently located at 15 various points between the carburetor and the engine to insure a thorough mixing of the gas.

A further object is to provide a mixer which can be secured in place without 20 changing the ordinary construction of the engine parts and may be used either singly or in any desired number to give the desired results.

With these and other objects in view the 25 invention consists in certain novel features of construction, and combinations and arrangements of parts as will be more fully hereinafter described and pointed out in the claim.

30 In the accompanying drawings—

Figure 1 is a view in side elevation illustrating an engine, a carburetor and an intake manifold showing parts of the manifold in section to illustrate the locations of 35 my improved mixer.

Figure 2 is an enlarged view in longitudinal section on the line 2—2 of Figure 1.

Figure 3 is a perspective view of the mixer.

40 1 represents an internal combustion engine, 2 a carburetor and 3 an intake manifold connecting the carburetor with the engine cylinders, and I have illustrated my improved mixer 4 as located between the 45 manifold and the carburetor and between the manifold and the engine, and such an arrangement of a plurality of my improved mixers gives splendid results and insures a proper mixing of the gases.

50 My improved mixer comprises a cylindri-

cal casing 5 having a base flange 6 at one end perforated as shown at 7 for the reception of screws or bolts 9 to securely hold the mixer in proper position. The cylindrical casing 5 is provided at its ends and at suitable points between its ends with screens 8, these screens being preferably spaced an equal distance apart and arranged in any desired number. The screens are preferably of fine copper wire mesh although they may 60 be made of any suitable material which will cause the gas to be screened, breaking the globules of liquid into small atoms and causing a commingling of the liquid and the air to form a perfect gas.

65 By locating a mixer 4 between the carburetor and the manifold 3 and other mixers between the manifold and the engine, a thorough mixing is insured and such an arrangement is a convenient one because the 70 casing 5 of the vaporizer can be of such size as to fit snugly within the manifold pipe and be secured against movement by reason of the engagement of the base flange 6 with the ends of the manifold.

75 Various slight changes might be made in the general form and arrangement of parts described without departing from the invention, and hence I do not limit myself to the precise details set forth, but consider 80 myself at liberty to make such changes and alterations as fairly fall within the spirit and scope of the appended claim.

I claim:

The combination with an internal combustion engine, a carburetor and an intake manifold having branches and connecting the carburetor with the engine cylinders, of a mixer in the manifold at the end connected with the carburetor, and a mixer in 90 each branch of the manifold at its connection with a cylinder, the mixers each consisting of a cylindrical casing having a flange at one end and provided with screens across its ends and between the ends thereof, 95 the casings being arranged in the manifold with the flanges engaging the ends of the manifold.

LEAL L. MONTGOMERY.
